UNITED STATES PATENT OFFICE.

JOHN EDWARD ERGANBRACK, OF CHICAGO, ILLINOIS, ASSIGNOR TO BELL & GOSSETT COMPANY, OF CHICAGO, ILLINOIS, A CORPORATION OF ILLINOIS.

UNRESTRICTED-RETURN WATER HEATER.

Application filed July 17, 1926. Serial No. 123,226.

My present invention relates to the provision of a type of water heater in which the heat transfer elements consist of one or more pairs of converging or diverging tubes 5 communicating at their converging ends and secured in a transverse plate at their diverging ends. The heat transfer elements are associated either in a single pair or in a plurality of pairs with an exterior head to 10 receive the exterior connections for supplying water to and conveying it from the heat transfer elements, and means are provided for securing the head and the transverse plate of the heat transfer element or elements about the edge of a suitable aperture 15 in a boiler or other chamber in which water or another heated element is contained so that the tubes of each pair will be disposed vertically with respect to each other.

20 The divergent arrangement of the tubes of the heat transfer elements at their outer ends facilitates both a gravitational and pressure circulation therethrough. I have also secured a juncture between the tubes of 25 the heat transfer elements at their converging ends by means of a structure the parts whereof are brazed together and to the ends of the tubes so as to provide even a greater capacity at the place of juncture than either 30 tube separately or both together would afford. This arrangement is important as this unavoidable bend in the path of travel of the water during the heat transfer process offers the greatest impediment to a gravitational circulation, and by making the juncture 35 between the ingoing and outgoing tubes of the heat transfer portion of greater capacity I have both improved the circulation through the system and improved the juncture portion as a heat transfer element in 40 itself.

Accordingly as one or more pairs of heat transfer tubes are assembled at their diverging ends with a single transverse plate they 45 may be employed with a number of different exterior heads to facilitate assembly with a particular hot water circulating system and for the purpose of increasing the capacity of the apparatus for furnishing hot water.

50 The design of structure heretofore referred to is illustrated in the accompanying drawing, in which—

Fig. 1 is a side elevation, largely in central, longitudinal, vertical section, of a complete assembly of a pair of heat transfer

tubes with an exterior head and boiler plate;

Fig. 2 is a front elevation of the structure shown in Fig. 1;

Fig. 3 is a perspective of the structure for joining the inner or converging ends of the 60 heat transfer tubes, the relation of the tubes to this member being shown in dotted lines;

Fig. 4 is a central, longitudinal section through the converging ends of the heat transfer tubes and the means for securing a 65 juncture between them;

Fig. 5 is a transverse section of the structure shown in Fig. 4 on line 5—5 thereof;

Fig. 6 is a perspective of one of the converging ends of a heat transfer tube; 70

Fig. 7 is a perspective of the rear end plate of the structure for forming a junction between the heat transfer tubes;

Fig. 8 is a central longitudinal section of a different form of external head than that 75 shown in Fig. 1, shown in assembly with a boiler plate and the heat transfer element;

Fig. 9 is a front elevation of the structure shown in Fig. 8;

Fig. 10 is a rear elevation of the exterior 80 head shown in Fig. 8;

Fig. 11 is also a rear elevation of the structure shown in Fig. 8 indicating the relation of two pairs of heat transfer tubes thereto;

Fig. 12 is a perspective showing the relation of the rear ends of two pairs of heat transfer units when used together. 85

Similar reference characters have been employed throughout the several views to designate similar parts. 90

A single unit or heat transfer element consists of two tubes, 15 and 16, of equal length disposed vertically, that is, one above the other, and held in slightly converging or diverging relation by means of an anterior 95 or front plate, 17, and a posterior or remote juncture casing, 18.

The anterior plate, 17, is bored or otherwise perforated for the passage of the forward ends of the heat transfer tubes therethrough and is secured to the tubes a short distance back of their front ends by brazing or sweating or in any other desired manner. 100

The remote, or posterior, ends of the heat transfer tubes are provided a short distance in front of their rear ends with an exterior bead, 19. The member for securing a junction between the rear ends of the heat transfer tubes is formed by taking a suitable 110

length, 20, of a much larger tube and de-forming it until it is of an oblong outline, as shown in Fig. 5. The centers of the forward edges of this length of tube 20 are in-
 5 wardly compressed, as shown at 21 in Fig. 3, to enter between the converging ends of the heat transfer tubes 15 and 16. The rear edges of the heat transfer tubes are beveled as shown at 22 in Figs. 4 and 6, and when
 10 the heat transfer tubes are inserted in the front end of the length of tube 20 up to the beading 19, spelter is placed in the recess formed by the bevel 22 and the whole is heat-
 15 ed until the above described parts are sweat-
 20 ed together. A very good and dependable joint can be formed as above described, whereas if this operation is attempted by flooding the joint from the outside it will probably result in dissolving and removing
 25 some of the metal of the tubes 15, 16 or 20 in the hot spelter.

After this interior brazing has been done, a beveled rear end plate, 23, is inserted in the length of tubing 20, and spelter is again placed in the cavity formed by the bevel, when a final heating secures the entire structure in a unitary or integral mass of ample strength and large capacity, relative to the capacities of the tubes, and a somewhat
 30 more extended surface to which the surrounding heated medium transmits heat by conduction.

In Figs. 1 and 2 is shown a form of head which is extremely simple and which is ar-
 35 ranged to take the feed and discharge pipes directly into its face. This form of head comprises a casting 24 extended to provide ears 25 at its two opposite ends, which ears are perforated, as at 26, for the passage of
 40 stud bolts 27 tapped into the boiler plate 28. The forward face of the casting 24 is sub-stantially flat and this is bored and tapped at 29 and 30 for assembly with the supply and discharge pipes. The bores 29 and 30 com-
 45 municate with interior chambers 31 and 32, separated by a partition, 33, which extends rearwardly into the plane of the rear of the head. The chambers 31 and 32 open rearwardly through apertures 34 and 35 and
 50 the rear face 36 of the casting 24 substan-tially registers with the forward face of the plate 17 heretofore described.

The boiler plate is apertured at 37 for the passage of the tubes 15 and 16 and a soft
 55 metal gasket 38 is employed between the rear face of the plate 17 and the boiler plate which gasket, 38, has a lateral projection or rib, 39, extending into the aperture in the boiler plate so as to prevent contact between
 60 the tubes 15 and 16 and the boiler plate.

Another soft metal washer, 40, is inter-
 65 posed between the forward face of the plate 17 and the rear face 36 of the casting 24. Nuts 41 on the outer ends of the stud bolts
 65 27 hold the castings 24, plate 17, and wash-

ers 38 and 40, firmly to the boiler plate, 28, with any degree of force which may be de-sired.

The head shown in Figs. 9 to 11 inclusive, is similar to that shown in Figs. 1 and 2 in all essential details except the body portion of the head 24^a has extending therefrom a neck 42 on the outer end whereof is an enlargement 43, bored and tapped in its face at 29^a and 30^a, and also laterally both in its bottom and top at 44 and 45.

In the head shown in Figs. 9 to 11 inclusive, it appears how, by merely enlarging the rear opening 34^a, the same head may be used for one or a plurality of pairs of heat transfer tubes 15^a and 16^a.

It should be noted that in each form of head the internal transverse partition 33 and 33^a is transversely bored as at 46 and 46^a to provide a bleed hole so as to permit the flow of any air released from the water from lower compartments 31 and 31^a to upper compartments 32 and 32^a from which any such air is immediately discharged through the discharge connection.

In Fig. 12 is shown in fragmental detail the relation of the juncture casings 18, when two pairs of heat transfer units are em-ployed in a single head.

As will be seen from the foregoing de-scription taken in connection with the draw-
 95 ings, each pair of heat transfer tubes 14 and 15 are disposed vertically with respect to each other and at a slight angle to each other, so that when the axis of these tubes 100 is arranged horizontally the conduit pro-
 90 vided by the tubes and their juncture casing 18 either rises or falls throughout its entire length. This facilitates both the gravitational and pressure circulation through these 105 tubes, and the juncture casing 18, having a capacity larger than either of the tubes taken separately or combined, acts as a de-
 95 terrent to circulation at the bend or change of direction in the flow as little as possible.

Having described my invention what I claim as new and desire to secure by Letters Patent is,—

1. A water heater comprising a head hav-
 115 ing two vertically disposed chambers and means for effecting frontal exterior com-
 120 munication therewith, an opening into each chamber in the rear wall of said head, a heat transfer unit consisting of a pair of con-
 125 verging tubes, the diverging ends whereof are united by a transverse plate registering with the rear wall of said head, a casing joining the converging ends of said tubes having a cross-sectional capacity greater than the capacity of said respective tubes, and means for securing said head and trans-
 130 verse plate to an apertured boiler plate.

2. A water heater comprising a head hav-
 130 ing two vertically disposed chambers and means for effecting frontal exterior com-

munication therewith, an opening into each chamber in the rear wall of said head, a heat transfer unit consisting of a pair of converging tubes, the diverging ends whereof communicate respectively with the rear openings in said head, a casing joining the converging ends of said tubes, and means for securing said head and tubes to an apertured boiler plate.

5 3. A water heater comprising a head having two vertically disposed chambers and means for effecting exterior communication therewith, an opening into each chamber in the rear wall of said head, a heat transfer unit consisting of a pair of converging tubes, the diverging ends whereof communicate respectively with the rear openings in said head, a casing joining the converging ends of said tubes, and means for securing said head and tubes to an apertured boiler plate.

10

JOHN EDWARD ERCANBRACK.
